BOWED EXPANDER ROLL

Charles W. Shute, Boston, Mass., assignor to
 Thomas Leyland Machinery Co., Incorporated,
 Boston, Mass., a corporation of Massachusetts

Application October 24, 1939, Serial No. 300,955

6 Claims. (Cl. 26—63)

This invention is an improvement in bowed expanders of the Mycock type for cloth and other continuous web material, and in particular relates to the bobbins which are mounted on a stationary curved shaft, to form an articulated curved roll usually rotated by drawing the web material over it, but sometimes otherwise driven, the outward component of travel of the surfaces of the bobbins as they rotate in planes oblique to the travel of the material being utilized to open and expand the sheet of web material in both directions away from its middle line.

The bobbins comprising each roll are either interlocked or clutched together, or else fixed tightly in a rubber tube or cover, to ensure their turning in unison, so as to attain uniform spreading action across the width of the material. The present invention is concerned with the uncovered type of expander, in which the metal bobbins come directly into contact with the material being stretched.

In my prior Patent No. 2,131,692, granted Sept. 27, 1938, I have disclosed an improved construction of uncovered expander bobbin in which the adverse effect of leaving the clutch dogs, which cause the bobbins to turn in unison, exposed to contact with the material being stretched is avoided. Briefly, this is accomplished by forming the ends of the cloth-engaging surface of each bobbin of continuous and unbroken circular shape, with the clutch dogs which engage and drive the adjacent bobbin, and also the recesses receiving the corresponding dogs of such adjacent bobbin, located wholly below and shielded by the cloth-engaging surface of one or other of the adjacent bobbins.

It has been found that under certain circumstances the selvage of the cloth being stretched will enter the space left between these circular ends of the substantially cylindrical cloth-engaging surfaces of two adjacent bobbins, since this space extends clear around the entire circuit of the roll at right angles to the axis thereof at such location. On account of the outwardly-diverging action of the expander roll on the fabric, the selvage of the cloth is itself traveling very nearly at right angles to the axis of the roll at such location, and on entering this substantially annular space described the selvage can and sometimes does become folded over, resulting in the formation of a doubled edge which gives trouble in subsequent finishing operations.

Also, because the warps of the traveling cloth run practically in line with this space between

adjacent bobbins, there is a tendency for such space to crease or mark light fabrics.

The object of the present invention is to remedy these minor faults in the patented structure, so as to enable its full benefit to be realized, and to these ends it provides a novel construction embodying the principle of disposing the joint between two adjacent bobbins of a bowed expander roll so that no portion of such joint or space 10 runs at right angles to the axis of the roll at such location, but instead runs always at some other angle, so that the joint or gap will traverse back and forth across the warps and thus both avoid the entry and consequent folding of the selvage 15 within the space and also distribute any mark or track of the gap back and forth across the warps so that it will not be visible or conspicuous to the eye. This improved result may be attained by any desired shaping of the ends of the cloth-engaging surfaces of the adjacent bobbins which 20 will cause such ends to be other than circular, that is, other than a straight line when the development of such end is projected onto a plane surface. Preferably, the ends will be made in the 25 shape of sinuous or undulating curves, though they may equally well be made in zigzag form. To keep the joint or space between adjacent bobbins as narrow as possible, the opposing ends of 30 two adjacent bobbins will be of identical but complementary shape, while the interengaging clutches below the cloth-engaging surfaces will be employed as in the patent to prevent actual contact between the ends of the cloth-engaging 35 portions of the bobbins. Also, to maintain this spaced relation of such ends of adjacent bobbins during the course of unavoidable wear of the co-engaging surfaces of the driving clutches, slight departures are made from the sine curve employed in giving the ends an undulant shape, as 40 by cutting away the material forming the ends of the cloth-engaging surfaces at the points where the slope of such curve is at its steepest.

Other objects of the invention, and the manner of their attainment, are as made plain hereinafter.

Illustrative embodiments showing the invention in three preferred forms are shown in the accompanying drawing, in which,

Fig. 1 is an elevation of a portion of a bowed expander roll, taken at the left-hand side of the center of such roll, illustrating two adjacent bobbins of my improved construction in working relation upon their curved shaft.

Fig. 2 is a development on a plane surface of a modified form of the respective curves of the op-

posed ends of the cloth-engaging surfaces of the two bobbins of Fig. 1, shown with the axes of the two bobbins in alignment.

Fig. 3 is an elevation of a single bobbin having the ends of its cloth-engaging surface made in zigzag form.

Fig. 4 is a similar elevation of a single bobbin having the ends of its cloth-engaging surface formed in a simple curve.

The stationary shaft 1 of the bowed expander is formed throughout its length with the customary uniform curvature. The cloth-engaging surface of each bobbin 3, 4, is provided with the usual sharp annular ridges or teeth 5 of saw-tooth shape in profile having a rake in the proper outward direction from mid-width of the roll, for enhancing the grip on the cloth, and the usual self-lubricating bushings 7 are fixed within the ends of each bobbin to bear against the shaft 1. In accordance with the patent named hereinbefore, clutch-dogs 9 of partly segmental shape are formed on both ends of each bobbin at locations well below the cloth-engaging surface thereof, with intervening recesses 11 to receive the corresponding clutch-dogs of the adjacent bobbin. The interengagement of these dogs and recesses compels rotation of all the bobbins in unison, as usual, and the bottoming of the clutch-dogs within such recesses maintains the ends of the cloth-engaging surfaces of each two adjacent bobbins in spaced relation to each other.

In accordance with the invention, the ends 13 of the cloth-engaging surfaces of each bobbin in Figs. 1 and 4 are formed in the shape of sinuous curves, that illustrated in Fig. 1 comprising two complete cycles of a sine curve, and that in Fig. 4 comprising a single cycle of a sine curve. The curves on opposite ends of each bobbin are identical and complementary, and preferably are identical in shape throughout the entire series of bobbins forming a roll. Thus, as the roll rotates, there will be clearance avoiding wear between the opposing ends of the cloth-engaging surfaces of each two adjacent bobbins as the entire series of bobbins rotates in unison, as in the patent, and yet the position of the clearance gap will shift back and forth along the axis of the roll with respect to any given fixed point in space, such as at the place where the adjacent ends approach most nearly together at the concave side of the roll. Thus the gap traverses back and forth across the warps of the cloth being drawn around the roll, which warps travel in approximate alignment with the ridges 5, and any mark left by the ends of the bobbin on fine goods is rendered harder for the eye to perceive.

Because the selvages of the fabric likewise travel in approximate alignment with the ridges 5, while the gap between adjacent rolls traverses back and forth across these ridges, there is no portion of the gap having any substantial extent in the direction of extent of the selvages, and therefore the selvage either is prevented from entering the gap because of such disalignment, or if it enters at the high point of the curves it is immediately lifted out again by engagement with the oncoming ends of the ridges 5 which are intersected by the curve at the points marked 15. As is obvious, there is no possibility of the selvage of the tightly-drawn fabric being doubled over or under by entering the gap.

Fig. 2 shows a modification of the sine curve or

curve of simple harmonic motion, which has been found useful in certain instances in prolonging the useful life of the bobbins. As wear develops between the driving shoulders of the clutches 9 and their sockets 11, it results in a slight relative axial rotation between the two bobbins involved, tending to narrow the gap until contact occurs between the ends of the cloth-engaging surfaces of adjacent bobbins at and adjacent the points where the slopes of the respective curves are the steepest, i. e., at the points where each curve would cross its horizontal axis when drawn on a graph. To prevent such contact, with the resulting burring of the ends of the cloth-engaging surfaces which tends to mark or pull threads in the fabric being stretched by these rolls, the space between adjacent rolls is widened slightly at these localities by departing from a true sine curve at the points in each where its slopes are the steepest, cutting away or concaving the terminal end of each bobbin at such points. This is diagrammatically represented in Fig. 2 in which the meeting ends of the two bobbins 3, 4, illustrated in Fig. 1 are shown in development as they would appear when unrolled while the bobbins are in a coaxial or aligned relation, (only 1 1/2 cycles being shown). The opposing edge of each bobbin is relieved slightly at the point indicated at 17 and shaped as indicated in solid lines, the original sine curve being portrayed throughout this interval in dotted lines. This modification allows a considerable amount of wear of the clutches and consequent relative rotation of the bobbins to take place before contact between the ends of the cloth-engaging surfaces can occur.

The modified form shown in Fig. 3 has been found useful in certain instances, the true zigzag line 13 followed in forming the salient and reentrant angles at the ends of the cloth-engaging surfaces being easier to produce under certain processes of machining and in certain materials. Its operation in preventing the marking and doubling of the selvage of the fabric is as in the form first described.

While I have illustrated and described certain forms in which the invention may be embodied, I am aware that many modifications may be made therein by any person skilled in the art, without departing from the scope of the invention as expressed in the claims. Therefore, I do not wish to be limited to the particular forms shown, or to the details of construction thereof, but

What I do claim is:

1. In a bowed cloth expander, in combination, a curved shaft, and a plurality of bobbins rotatably mounted on the shaft, each having its cloth-engaging surface terminating in a sinuous curve and with the convex portions of such curve on one bobbin occupying the concave portions of the sinuous curve on the adjacent bobbin, and means wholly below the cloth-engaging surfaces holding the sinuously-curved portions of adjacent bobbins apart from each other.

2. In a bowed cloth expander, in combination, a curved shaft, and a plurality of bobbins rotatably mounted on the shaft, each having the terminal margins of its surface which engages the cloth which is to be expanded formed with alternate salient and reentrant portions and with the salient portions on one bobbin occupying the reentrant portions on the adjacent bobbin,

and means apart from the thus formed portions causing adjacent bobbins to rotate in unison.

3. In a bowed cloth expander, in combination, a curved shaft, and a plurality of bobbins rotatably mounted on the shaft, each having a surface which engages the cloth which is to be expanded formed with sinuous curves at its ends, and the bobbins having mutually interlocking projections additional to the portions formed with sinuous curves compelling adjacent bobbins to turn in unison.

4. In a bowed cloth expander, in combination, a curved shaft, a plurality of bobbins rotatably mounted on the shaft, each having the terminal edges of its cloth-engaging surface disposed at other than a right angle to its axis throughout substantially the entire circumference of the bobbin, and means below and apart from such terminal edges causing adjacent bobbins to rotate in unison.

5. In a bowed cloth expander, in combination, a curved shaft, and a plurality of bobbins rotatably mounted on the shaft, each having the terminal edges of its cloth-engaging surface dis-

posed at other than a right angle to its axis throughout substantially the entire circumference of the bobbin and the bobbins having mutually interlocking projections extending axially beyond the end of the cloth-engaging surface of the bobbin on which they are located, compelling adjacent bobbins to turn in unison, such projections being covered by the cloth-engaging surface of the adjacent bobbin where they extend within the length of such latter bobbin.

6. In a bowed cloth expander of the uncovered type in which the bobbins come directly into contact with the cloth being stretched, a series of bowed expander bobbins each having the ends 15 of its cloth-engaging surface formed in the shape of a sine curve, modified at the points where the slope of the curve would otherwise be the steepest by reducing such slope, the convex portions of the sine curve on one bobbin occupying the 20 concave portions of the sine curve on the adjacent bobbin, and means wholly below the portions thus curved causing adjacent bobbins to rotate in unison.
